Patented May 2, 1916.

UNITED STATES PATENT OFFICE.

CHARLES BECKER, OF MILWAUKEE, WISCONSIN.

RAIL-CLAMP.

1,181,563.

Specification of Letters Patent. Patented May 2, 1916.

Application filed April 9, 1915. Serial No. 20,298.

To all whom it may concern:

Be it known that I, CHARLES BECKER, a citizen of the United States, residing at Milwaukee in the county of Milwaukee and State of Wisconsin, have invented new and useful Improvements in Rail-Clamps, of which the following is a specification.

The present invention relates to improvements in railway construction, the primary object of the invention being to provide simple but effective means for securing a rail upon a tie.

With the above and other objects in view, the improvement resides in the construction, combination, and arrangement of parts set forth in the following specification and falling within the scope of the appended claims.

In the drawing: Figure 1 is a side elevation, partly in section, of a tie constructed in accordance with the present invention and illustrating the means for securing a rail thereto, Fig. 2 is a sectional view approximately on the line 2—2 of Fig. 3, and Fig. 3 is a transverse sectional view approximately on the line 3—3 of Fig. 1.

The tie employed with my improvement is preferably constructed of plastic material, the same being of the proper length and width and is reinforced by a plurality of longitudinally extending bars 12 as well as metallic members 13, the same being curved upon themselves to provide a plurality of convolutions and the said convolutions are arranged adjacent the inner sides of the reinforcing rods 12, as clearly illustrated in Figs. 1 and 3 of the drawing. The tie preferably has its central portion curved upwardly, providing the lower face of said tie with a transverse arched portion 18, so that the said tie may be readily received within the road-bed and effectively tamped therein to prevent both the lateral and longitudinal movement thereof. The longitudinal edges of the tie are preferably beveled, as indicated by the numerals 20, and the sides of the tie are continued for a suitable distance above the said beveled corners 20 in vertical and parallel planes, as indicated by the numerals 21, and from thence the said sides are beveled inwardly toward the horizontally straight top of the tie which is disposed to the opposite ends thereof. The said horizontally straight face, adjacent each end of the tie is inclined to the said ends and the said horizontal face adjacent the said ends is provided with trans-

verse substantially rectangular depressions 24. These depressions are of a width greater than the width of the base flanges of the rails 1, and are adapted to receive 60 therein rail plates 2 upon which the said rails 1 rest. These rail plates comprise a central horizontally straight portion of a width approximately equaling the width of the base flange of the rails 1, the said base 65 being provided with vertically disposed flanges 2' which are adapted to contact with the opposite longitudinal edges of the base flange of the rail and the plates are provided with opposite downwardly inclined portions 70 2^a which terminate in vertical flanges 2^b, the said flanges 2^b being embedded within the plastic body of the tie and being provided with openings 2^c through which the longitudinal rods 12 pass. The upper face 75 of the tie is formed to receive the angular flanges 2^a of the tie plate 2, and the said tie, at its underface, and directly below the rail 1 is provided with a transverse pocket or passage 14, a rod 6 being extended 80 through the said passage at the upper wall thereof, and the said rod provides a fulcrum member for a rocker plate 5. This rocker plate is provided adjacent its ends with openings 10 and 11, each adapted to 85 receive the ends of cross sectionally rectangular bolts 15 and 16 respectively, the bolt 16 being provided with a head which abuts against the lower face of the rocker plate 5 and both of said bolts 15 and 16 project 90 through substantially rectangular openings *x* and *y* in the tie proper and also extend through openings in the tie plate 2, the said openings being disposed at the juncture of the inclined flanges 2^a with the base proper 95 of the said plate, so that the rods contact with the opposite edges of the rails 1.

The numeral 9 designates a washer which is arranged to surround the rounded and upper end 4 of the bolt 16 and the numeral 18 designates a nut for the said threaded and rounded end 4 of the said bolt 16. The bolt 15 is provided with a lateral head 3 which contacts with one of the edges of the base flange of each of the rails 1, and the 105 opposite end of said bolt 15 is provided with a rounded and threaded extension which passes through the opening in the rocker plate 5 and the numeral 7 designates a nut which engages with the said bolt.

From the above description, taken in connection with the drawings, it will be noted

that the washer 9 contacts with the base of the rail 1 opposite that engaged by the head 3, and it will be understood that the bolt 15 may be arranged upon the rail and 5 the rail positioned upon the plate 2, after which the bolt 16, which, it should be stated, is previously arranged within the opening 10 of the rocker plate 5 may be drawn upwardly of the tie and the washer 9 inserted 10 thereon. Thereafter the nut 18 is applied to the threaded portion 4, the nut adjusted to force the washer 9 against the base flange of the rail, and thus effectively secure the rail upon the tie.

15 It will be further noted that the bolts 15 and 16 are arranged angularly with relation to each other so that no direct vertical pull will be exerted either upon the head 3 of the bolt 15 or the washer 9 of the bolt 16 20 and as a consequence the liability of the accidental separation of the nuts from the bolts will be reduced to a minimum if not entirely obviated, and further, if desired, the nut may be rigidly secured to the bolt 15.

25 Having thus described the invention, what I claim is:

1. The combination with a tie having a depression in the underface thereof, and a rod secured in the tie and passing through 30 the depression, a rocker plate fulcrumed upon the rod, a rail upon the tie above the rocker plate, and angularly arranged rods adjustably connected with the rocker plate and engaging with the edges of the rail.

2. The combination with a tie having a 35 rail thereon, of a rocker plate disposed in a depression in the underface of the rail, angularly extending adjustable rods connected with the rocker plate, one of said rods having a hooked end engaging with one of the 40 edges of the rail, and an adjustable element upon the other rod engaging with the opposite end of the rail.

3. The combination with a tie having a rail plate thereon and a rail arranged upon 45 the plate, and said tie having a depression in its underface below the rail, of a laterally extending rod and a rod passing through the depression, a rocker plate having a central round depression engaging with the 50 rod, bolt members passing through angular openings in the tie and in the rail plate and adjustably connected one with each of the opposite ends of the rocker plate, one of said bolt members having its projecting end 55 hooked and engaging with one of the longitudinal edges of the rail, the other bolt having its projecting end threaded, a washer upon the said threaded end and engaging with the other edge of the rail, and a nut for 60 forcing the washer into such engagement.

In testimony whereof I affix my signature in presence of two witnesses.

CHARLES BECKER.

Witnesses:
